UNITED STATES PATENT OFFICE

FRED W. LEUTHESSER, OF OAK PARK, ILLINOIS

DESIGN FOR AN AIR VALVE

Application filed May 31, 1929. Serial No. 31,488. Term of patent 14 years.

To all whom it may concern:

Be it known that I, FRED W. LEUTHESSER, a citizen of the United States, residing at Oak Park, in the county of Cook and State of Illinois, have invented a certain new, original, and ornamental Design for Air Valves, of which the following is a specification, reference being had to the accompanying drawing, forming part thereof.

The figure is a perspective view of an air valve showing my new design.

I claim:

The ornamental design for an air valve, as shown.

FRED W. LEUTHESSER.
